UNITED STATES PATENT OFFICE.

SALLY M. LEVY, OF MILWAUKEE, WISCONSIN.

KNIT FOUNDATION FOR MITTENS AND GLOVES AND METHOD OF MAKING THE SAME.

SPECIFICATION forming part of Letters Patent No. 273,111, dated February 27, 1883.

Application filed November 6, 1882. (No model.)

To all whom it may concern:

Be it known that I, SALLY M. LEVY, of Milwaukee, in the county of Milwaukee, and in the State of Wisconsin, have invented certain new and useful Improvements in Knit Foundations for Mittens and Gloves; and I do hereby declare that the following is a full, clear, and exact description thereof.

My invention relates to knit fabrics; and it consists in a web of peculiar construction, together with the method of cutting the same for forming the foundation of mittens and gloves, and also in the mitten or glove blank thus constructed.

15 In the drawings, Figure 1 represents a circular web with thumbs knit thereto, and showing in dotted lines where it is to be cut. Fig. 2 represents the same web after it has been cut on the dotted lines of Fig. 1 and folded open. Fig. 20 3 represents one-half or hand section of the web shown in Fig. 2 slit for forming the foundation of a glove; and Fig. 4 is a view of a circular seamless web like that shown in Fig. 1, but without the knitted thumbs.

25 A is my circular seamless web, knit on any ordinary circular-knitting machine, which web in Fig. 1 has the thumbs B B' knit thereon. Having knit my web, I may full it, if desired, or not, and then I proceed to cut in on the path of 30 the dotted lines shown in Fig. 1, so as to make the blanks for two mittens (or gloves) out of each web. I cut the web on one side from a at the root of the thumb B to the point a', as indicated by the double row of dotted lines 35 at the left of said figure, and on the opposite side of the web I cut the fabric from b at the root of the thumb B' to the point b', as indicated by the single row of dotted lines at the right of said figure, and I also cut the fabric 40 from the point a' to b and from the point a to b'. In Fig. 2, I have left a short part of the fabric on one of these latter lines uncut, as at c, so as to more clearly show the original relative positions of the two mitten-blanks in the 45 web; but it will be understood that in practice I cut wholly along the line, so as to separate the two blanks.

In order to convert the mitten-blanks into 50 glove-blanks it is only necessary to slit the hand part of the blank, as at d d d in Fig. 3, and in this condition the mitten or glove

blanks may be furnished to the glove-makers, who supply leather, canvas, or other facing for the palm or inside of the mittens or gloves, and put them on the market in that shape; but my 55 invention is complete when I have finished the foundation, and the goods are sold in this condition from the knitting-factories, the leather or other palms or linings forming no part of my invention necessarily.

In Figs. 2 and 3 the vertical shade-lines indicate single thickness or cut portions of my web and the diagonal shade-lines the uncut or circular portions, and one great advantage of mittens and gloves made from my improved 65 blanks lies in the fact that the wrists and thumbs are seamless. Another advantage is, 70 whereas with the old method the palm or inside of each glove or mitten had either to be cut out and thrown away, if made from a circular web before the facing was applied, or otherwise the article would be thick and clumsy, and hence in flexible goods there was considerable waste, which is avoided by my invention, 75 while if the mitten were cut out of a flat web there would be an objectionable seam in the wrist, as well as more or less waste also.

In Fig. 4, I have shown a thumbless web, 80 which is to be cut exactly as shown in Figs. 1 and 2. The object of this is to supply knit foundations to such glove-makers as prefer to make the thumbs of their goods entirely of the same material as the palm, but otherwise these 85 blanks are knit and cut exactly like the others.

While I have shown my webs with the thumbs on opposite sides, so as to make a pair of mittens or gloves out of each web, it is obvious that the said thumbs may be both knitted on 90 the same side of the web, in which event I would have two "lefts" or two "rights" instead of a "pair" of blanks after cutting the web, while in the plain web shown in Fig. 4 there are no thumbs, and hence the mitten or 95 glove blanks would be always in pairs necessarily.

Having thus described my invention, what I claim as new, and desire to secure by Letters Patent, is—

1. A blank or foundation for knit mittens and gloves, having a seamless wrist and a

palmless hand portion, substantially as shown and described, and for the purpose set forth.

2. A blank or foundation for knit mittens and gloves, having a seamless wrist and thumb and a palmless hand portion, substantially as shown and described, and for the purpose set forth.

3. The process of making blauks or foundations for mittens or gloves, consisting in knitting a circular seamless web or tube, and then cutting the same transversely from the point a to a' on one side, and from the point b to b' on the other side, and also cutting longitudi-

nally from a to b' and from a' to b , whereby the blanks or foundations for a pair of mittens or gloves are formed from a single circular web with seamless wrists and palmless hand portions, and without waste, substantially as shown and described, and for the purpose set forth.

In testimony that I claim the foregoing I have hereunto set my hand, on this 16th day of October, 1882, in the presence of two witnesses.

SALLY M. LEVY.
